To all whom it may concern:

Be it known that I, Leclare H. Amrine, a citizen
of the United States, residing at 532 Roscoe
Street, Chicago, in the county of Cook and State
of Illinois, have invented a new, original, and
ornamental Design for Gaming Machine Cases,
of which the following is a specification, refer-
ence being had to the accompanying drawing,
forming part thereof.

Fig. 1 of the drawing shows a top view.

Fig. 2 shows a front view and

Fig. 3 shows a side view of the design.

The appearance sought to be represented is
that of a rectilinear object with softened cor-
ners forming the background for a series of
needle like, obelisk figures pointing in a general
upward direction.

I claim:

The ornamental design for a gaming machine
case as shown and described.
